UNITED STATES PATENT OFFICE.

H. C. SPALDING AND G. STICKNEY, OF HARTFORD, CONNECTICUT.

ROTARY PUMP.

Specification of Letters Patent No. 8,893, dated April 20, 1852.

To all whom it may concern:

Be it known that we, HENRY C. SPALDING and GAGE STICKNEY, of Hartford, in the county of Hartford and State of Connecticut, have invented a new and Improved 5 Rotary Pump; and we do hereby declare that the following is a full, clear, and exact description of the construction and operation of the same, reference being had to the 10 annexed drawings, making a part of this specification, in which—

Figure 1, is a front view of the pump in elevation. Fig. 2, is a horizontal section of the case taken at the line X, X, Fig. 1, the 15 flanch and shaft not being bisected. Fig. 3, is a front view in elevation, the case being cut vertically through the center, and the part nearest the eye removed, a portion of the front of the eduction tube being also removed, as also the front of the chamber immediately over the injection pipe adjoining 20 one of the side plates and inclosing the aperture in the side plate. The screw and shaft is not bisected.

Similar letters of reference indicate corresponding parts in each of the several figures.

The nature of our invention consists in inclosing within a circular case a shaft on 30 which is a spiral flanch, said flanch being a portion of a thread of a screw, the outer surface of the spiral flanch by the aid of suitable packing, works closely against the inner surface of the case; a portion of the 35 flanch at each of its ends is bent out of the spiral curve and forms right angles with the shaft, these portions of the flanch bear against the side plates of the case; there is an induction aperture through one of the 40 side plates and an eduction aperture through the other and the ends of the spiral flanch above mentioned pass over and close both these apertures at necessary intervals as the flanch revolves; the ends of the flanch passing 45 each other as the flanch makes rather more than one revolution around the shaft, the above arrangement in connection with a sliding valve (which will be hereafter described) for preventing back draft when 50 both the apertures are open constitute the invention.

To enable others skilled in the art to make and use our invention we will proceed to describe its construction and operation.

A, is a circular case, having the side plates B, B', attached to it by screw bolts (a), in

the center of the case A, a shaft C, is placed, around which is a spiral flanch D, said flanch forming a part of a thread of a screw this will be clearly seen by referring to Figs. 2, 60 and 3, the outer surface of this flanch works tightly against the inner surface of the case A, by means of any suitable packing (b); the ends (c) (c') of the flanch pass each other see Fig. 3, or in other words the flanch makes rather more than one revolution 65 around the shaft C'.

(d) is the induction aperture through the side plate B, and (e) is the eduction aperture through the side plate B', these apertures pass through the side plates at opposite points see dotted lines in Fig. 3.

E, is the induction pipe which passes into a well or reservoir, this pipe connects with a chamber F, which is attached to the side 75 plate B, and covers the induction aperture (d) Figs. 2 and 3.

G, is the eduction tube attached to the side plate B', the water is forced into this tube through the eduction orifice (e).

H, is a shaft which passes through the shaft C, one end of the shaft H, fits in the center of the inner side of the side plate B', the other end passes through a stuffing box (f) at the center of the side plate B, the 85 power is applied to this shaft.

I, is a valve which vibrates through the eduction aperture (e), this valve is pressed out of the case A, and into the eduction tube G, by the flanch D, as it rotates, the end 90 (g) of the valve bearing against the side of the flanch see Figs. 2 and 3, the end (g) of the valve is so shaped as to fit snugly against the side of the flanch and conform to its curvature, and any wear caused by 95 friction will only tend to make the end (g) of the valve sit closed to the side of the flanch.

J, is a spiral spring inclosed within the eduction tube one end bearing against the end (h) of the valve I, this spring tends to keep the end (g) of the valve always close against the side of the flanch, one side of the valve works in a recess in the inner surface of the case A, and the other side bears 105 closely against the shaft C, that is as much of the valve as is within the case.

The several parts of the pump are now described and the operation now remains to be described.

Power being applied to the shaft H, the flanch D, revolves within the case A, the

outer surface of the flanch working tightly against the inner surface of the case by the aid of any suitable packing (b), by the revolutions of the flanch a vacuum is formed 5 within the case and the water is drawn from the well or reservoir through the induction pipe E, and passes into the case through the induction aperture (d) it is then carried around by the spiral flanch D, and forced 10 through the eduction tube G, the water passing into the eduction tube through the eduction aperture (e) it will be remembered that the two ends of the flanch (c) (c') are bent out of the spiral curve so that they 15 bear against the inner surface of the side plates. By this arrangement both apertures (d) (e) are closed while the slide is thrown out from the case, as the ends (c) (c') pass each other, or the flanch makes rather more 20 than one revolution on the shaft C, and when the end (c') adjoining the side plate B', has passed the eduction aperture the slide I, is thrown by the spiral spring across the end of the flanch (c') adjoining the side 25 plate B', and against the side of the flanch as seen in Fig. 2. This valve then is a cut off, and prevents any back draft or reaction when the ends (c) (c') of the flanch do not cover the induction and eduction apertures, 30 the ends of the flanch are so bent that the induction aperture is closed till the end (c')

of the flanch has passed the eduction aperture and the slide I, thrown against the side of the flanch by the spiral spring as seen in Fig. 2, the end (c) of the flanch 35 then passes the induction aperture and the water is allowed to enter the pump.

The above arrangement of pumps is simple, is not liable to get out of repair, and in practice works well by employing suitable packing on the outer surface of the flanch leakage is not likely to occur and the valve works perfectly tight as the wear attendant upon friction only serves to fit the end (g) of the valve closer to the side of 45 the flanch.

Having thus described the nature and operation of our invention, what we claim as new and desire to secure by Letters Patent, is—

The spiral flanch D, working within a circular case A, said flanch being constructed as described in combination with the sliding valve I, the spiral flanch and valve operating in the manner and for the purpose substantially as herein shown and specified.

HENRY C. SPALDING.
GAGE STICKNEY.
